UNITED STATES PATENT OFFICE.

HENRY V. DEMPSTER, OF MINNEAPOLIS, MINNESOTA.

AEROPLANE FLYING TOY.

Application filed July 13, 1925. Serial No. 43,094.

This invention relates to a toy, and particularly to such a toy in the form of an airship or aeroplane.

It is an object of this invention to provide a very simple, pleasing, efficient and inexpensive toy aeroplane.

It is a further object of the invention to provide a toy aeroplane made from sheet material comprising a very small number of 10 blanks or pieces, which blanks are folded to constitute an aeroplane having a hollow fuselage adapted to hold a plane, said fuselage having a propeller at one end held by a single piece of wire being supported by a 15 string at one end of a rod, which string is secured by a single wire member engaging the fuselage.

It is another object of the invention to provide a blank of sheet material adapted to 20 be folded to constitute the fuselage of the toy aeroplane and adapted to receive a plane and supporting wheels.

It is still another object of the invention to provide a novel blank adapted to form 25 the supporting wheels for the aeroplane.

These and other objects and advantages of the invention will be set forth in the following description made in connection with the accompanying drawings in which like 30 reference characters refer to the same parts throughout the different views, and in which,

Fig. 1 is a plan view of the device;

Fig. 2 is a view in side elevation thereof, 35 certain portions being broken away and others shown in vertical section;

Fig. 3 is a vertical section taken on the line 3—3 of Fig. 2, as indicated by the arrows;

Fig. 4 is a vertical section taken on the line 4—4 of Fig. 2, as indicated by the arrows;

Fig. 5 is a vertical section taken on the line 5—5 of Fig. 2, as indicated by the 45 arrows;

Fig. 6 is a developed view of the blank used to form the fuselage and other parts of the device;

Fig. 7 is a developed view of the blank 50 used to form the supporting wheels; and

Fig. 8 is a view of the piece used to form the vertical tail rudder of the aeroplane.

Referring to the drawings, a toy aeroplane is shown comprising a fuselage 10, a plane 55 11 secured thereto, supporting wheels 12 secured to the fuselage, a propeller 13 secured

to the front of the fuselage by a member 14, a vertical tail rudder 15, a rod 16 having a head member or pin 17 projecting longitudinally thereof at one end receiving the 60 looped end of a string 18 which is secured at the other end and a bow member 19 having its ends secured in the fuselage 10 at each side of the plane 11.

The fuselage 10 is folded up from a one-piece blank shown in Fig. 6. This blank comprises a central portion 10^a of rectangular shape divided into a plurality of zones 10^b by lines 10^c extending longitudinally from said central portion. The blank also 70 comprises end portions 10^d and 10^e which are tapered outwardly or have outwardly converging side edges. The end portion 10^e is divided into a plurality of zones 10^f by lines 10^g and it will be noted that said lines 75 10^g converge toward their outer ends so that the zones 10^f taper toward the outer ends and it will also be noted that the inner ends of the zones 10^f are co-extensive with and abut the adjacent ends of the zones 10^b, the inner ends of lines 10^g meeting the outer ends of the lines 10^c. The end portion 10^d is also divided into zones 10^h by lines 10ⁱ which also converge toward their outer ends so that zones 10^h are tapered toward their outer ends. The lines 10ⁱ, at their inner ends, align with the lines 10^c so that the inner ends of zone 10^h are co-extensive with and abut the adjacent ends of zones 10^b. Each of the end portions 10^e and 10^d has an 80 outwardly extending pointed triangular notch 10^j cut therein at the outer lines 10^g and 10ⁱ respectively. It will be seen that the central zone 10^b is joined to the longitudinally aligned zones 10^f and 10^h but that the 85 other zone on the end portions 10^e and 10^d are separated from the adjacent zones of the central portion 10^a.

The blank is also provided with openings or slits 10^k, the same being in the central and end portions and along the outermost lines 10^c, 10^e and 10ⁱ, respectively, at one side of the blank. The blank also has projecting tabs or tongues 10^l projecting from its central and end portions at the opposite edge from which the slits 10^k are adjacent, which tongues are adapted, when the blank is folded, respectively to enter the slits 10^k. The end portion 10^e, which is the front portion of the blank, has a terminal extension 10^m having lateral portions 10^{m'} and an end portion 10^{m''}, said portions being adapted 105 110

to be folded along lines indicated as 10^a and 10^b , respectively. The end portion 10^d , which is the rear portion, has a centrally projecting strip 10^e which connects the central zone 10^a with the horizontal tail rudder portion 10^g , said portion having a central slit 10^f formed therein, said central zone 10^a also having a central longitudinal slit 10^h at its rear end. The portions 10^e and 10^g are adapted to fold along the lines 10^i . The central zone 10^b has slits 10^j at each side thereof on the lines 10^k adjacent its forward end. The outer zone 10^h and 10^i are also provided with holes 10^l adjacent their inner ends, and the central zone 10^a and the members 10^m are provided with centrally disposed holes 10° . The rear portion of the outer zones 10^h have recesses 10^p cut therein forming the edges 10^q .

20 The wheels 12 of the aeroplane are formed from a blank having a central narrow portion 12^a , at each end of which is a pair of circular portions 12^b arranged in substantially tangential relation and connected adjacent their point of tangency. The outer circular portions 12^b have projecting therefrom strips or tabs 12^c , said tabs having narrowed inner portions and also having formed therein inwardly extending slots 12^d .

25 The circular portions 12^b are adapted to fold along the dotted lines 12^e therebetween and the portion 12^a is adapted to be folded along the dotted lines 12^f . The vertical tail rudder 15 is formed from a piece 15^a shown in Fig. 8, having extending vertically thereinto a slot or slit 15^b . This slot forms the tongues 15^c and 15^d and said rudder has a right-angled recess at one side forming the edge 15^e .

30 In assembling the device the blank for the fuselage 10 is folded along the lines 10^a , 10^b and 10^c into polygonal shape, said shape being substantially square in cross section, as shown in Fig. 3. The central zone 10^a , 10^b and 11^f are at the bottom of the fuselage and the outer zones 10^a , 10^b and 10^h having thereon the tabs 10^k overlap respectively the zones 10^a , 10^b and 10^h at the other side of the blank and are at the top of the fuselage, the tongues 10^k entering the slits 10^f . When the blank is thus folded, the inner ends of the zones 10^a and 10^b at the outer side of the blank have their pointed ends or flaps 10^r and 10^s , as shown in Fig. 1, overlapping the adjacent zone 10^a at the top of the fuselage. The plane 11 which comprises merely a sheet of material shaped, as shown in Fig. 1, is then placed in position under the pointed ends 10^r and 10^s . The holes 10^s , in the respective end portions 10^a and 10^b are now in vertical alinement and the bow or bail member 19 has its ends inserted through these holes and the horizontal parallel portions at the ends of member 19 embrace the ends of the overlapped zones 10^a , 10^b and 10^h , as well as the inserted plane 11, as clearly shown in Fig. 2. It will also be noted that there is a triangular pointed portion 10^t and 10^u at the inner ends of zones 10^f and 10^h , respectively, at each side of the central zone, which portions are disposed inwardly of and overlapping the zones 10^b of the central portion 10^a when the fuselage is in folded condition, as clearly shown in Fig. 2. The fuselage being folded, as described, is held in folded position by the tongues 10^k and the member 19 and the end portion 10^m is then folded along the lines 10^a and 10^b , as shown in Figs. 2, 3 and 5; zone 10^m being spaced some distance inwardly of the zone between the lines 10^m . The holes 10^t then come into horizontal alinement and the member 14 is inserted through the propeller 13 and then through the holes 10^t , as shown in Fig. 5, said member 14 having a portion 14^a bent at right angles and extending downwardly inside of the zone 10^m and having another portion 14^b bent horizontally at right angles to extend through the hole 10^t in the central zone 10^t which is at the bottom of the fuselage. The member 14 has a circular portion formed in its outer end to prevent outward movement of the propeller 13. The member 14 thus holds the propeller 13 in position and assists in holding the end of the blank of member 10 in position. The portion 10° of the fuselage blank is now folded upwardly at a right angle along the inner line 10° and is then reversely folded along the center line 10° and is again bent or folded outwardly at a right angle along the outer line 10° , as shown in Fig. 4. The portion between the inner pair of lines 10^o thus closes the rear end of the fuselage and the portion 10^p is disposed in horizontal relation. The vertical tail rudder 15 is now placed in position with the portion 15^c projected downwardly through the inner slit 10^f and the portion 15^d projects downwardly through the outer slit 10^g in the horizontal tail rudder. The slit 15^b then embraces a portion between the inner and outer lines 10^o . It may be here stated, that there is a slit formed in the top of the folded fuselage 12 by the recesses 10^b which are cut in the rear ends of the outer zones 10^h , said slit being formed between the spaced edges 10^q of said recesses. The member 15^e passes through this latter mentioned slit in the top of the folded fuselage and the surface 15^e fits flat against the top surface of the horizontal rudder portion 10^g outwardly of the outer slit 10^g .

35 The blank for the wheels 12 is now folded upwardly along the lines 12^e to bring the circular portions 12^b into overlapping contacting relation. The blank is then folded downwardly along the lines 12^f . The projections 12^c then project vertically and

40 80 85 90 95 100 105 110 115 120 125 130

these projections are inserted through the slits 10^c and moved forwardly so that the slits 12^d embrace the thickness of the central bottom zone 10^b. The string 18 is now tied to the top central portion of the member 19, a loop formed in the other end of the string and disposed about the shank of the headed member 17 which is then inserted in rod 16. The rod 16 is, in practice, 10 from 15 to 24 inches in length.

In operating the device, the free end of the rod is held in the hand and the other end of the rod moved in a circular path about the head of the operator. The action 15 of the air on the propeller 13 causes the same to rapidly revolve and the plane 11 and the rudders 15 and 10^p hold the plane in upright position. The flight of an actual aeroplane is thus closely simulated.

20 From the above description it is seen that the applicant has provided a very simple and efficient toy and one which can be quickly and inexpensively made and assembled. The device comprises very few parts and 25 these are easily and cheaply secured. The toy when assembled is quite strong and durable. The same has been amply demonstrated in actual practice and found to be very successful and efficient.

30 It will, of course, be understood, that various changes may be made in the form, details, arrangement and proportions of the parts without departing from the scope of applicant's invention, which, generally 35 stated, consists in a device capable of carrying out the objects above set forth, in the novel parts and combinations of parts disclosed and defined in the appended 40 claims.

What is claimed is:

1. A toy aeroplane having in combination, a fuselage having a central portion and tapered end portions, said fuselage being 45 hollow and of polygonal shape in cross section and having forwardly and rearwardly projecting flap portions at its top, a flat plane inserted between said flap portions across the top of said fuselage, a wire or 50 rod member extending through the top of said fuselage at each side of said plane having spaced horizontal portions embracing the plane and the top layers of said fuselage, said wire member extending as a bow above said plane centrally and longitudinally thereof, a string fastened at the 55 top of said bow and secured at its other end to the end of a rod.

2. A toy aeroplane having in combination, a hollow fuselage of sheet material, 60 said fuselage being of polygonal shape in cross section and having a flat top portion, a plane extending transversely of and centrally secured to the top of said fuselage, 65 a revoluble propeller journaled on an axis extending centrally of said fuselage at the

front portion thereof and a member folded to form a pair of simulating supporting wheels secured to the bottom of said fuselage beneath said plane and a bail member secured to the top of said fuselage and clamp- 70 ing said plane in position.

3. A toy aeroplane comprising a hollow fuselage made from folded sheet material, a plane secured transversely of the top of said fuselage, said fuselage being formed 75 with a horizontal tail rudder, a vertical tail rudder secured to said fuselage and horizontal tail rudder, a pair of wheel-simulating members having tabs inserted in spaced slits in the bottom of said fuselage, a bail 80 member secured to the top of said fuselage centrally thereof, a string secured to the top of said bail member, and a rod pivotally secured to the other end of said string. 85

4. A blank for the fuselage of a toy aeroplane comprising a piece of sheet material having a central rectangular portion divided into a plurality of rectangular zones by longitudinal lines along which it is adapted to fold, an end portion at each end of said central portion each having converging sides and divided into a plurality of zones having their sides converging toward the ends of said pieces and their inner sides 90 abutting the respective ends of said first mentioned zones, and adapted to be folded along their dividing lines, the longitudinally divided zones of said central and end portions being adapted to form respectively the 95 sides of said fuselage.

5. The structure set forth in claim 4, and a terminal portion at the outer end of one of said end portions comprising zones separated by fold lines and adapted to form a 100 closure for one end of said fuselage. 105

6. The structure set forth in claim 4, and a terminal portion at one end of one of said end portions adapted to form a tail rudder for said fuselage. 110

7. The structure set forth in claim 4, said central portion having a central zone joined at its ends to the central zone in each of said end portions, the remaining zones in said end portions being separated from the respective abutting zones in said central portion, tabs projecting from the outer sides of the zones at one side of said piece and slots adjacent the other side of said piece for receiving said tabs. 115

8. The structure set forth in claim 4, said central portion having a central zone joined at its ends to the central zone in each of said end portions, the remaining zones in said end portions being separated from the respective abutting zones in said central portion, said blank having outwardly extending pointed recesses cut therein between the outer zone and the adjacent zone at each side of said 125 end portions. 130

9. A blank adapted to form a pair of members simulating wheels for a toy device comprising a sheet having spaced pairs of substantially circular tangentially arranged portions connected adjacent their point of tangency, said pairs being joined by a comparatively narrow strip extending therebetween, and short tabs projecting from the outer sides of the outer circular portion of each pair, said portions and strips having a common straight center line.

10. A toy aeroplane comprising a fuselage of polygonal shape in cross section having tapered end portions and folded along its edges and having overlapping superposed layers at its side, a plane extending transversely at the top of said fuselage, a member embracing said plane and the top layers of said fuselage, a string secured to said member, a rod secured to said string, and a wheel-simulating member secured to the bottom of said fuselage.

11. A toy aeroplane comprising a plural-

ity of blanks cut from sheet material forming a fuselage, a plane, a rudder, a propeller and simulated landing wheels, a bail and a propeller shaft connected to said fuselage, said bail and shaft being adapted to co-operate with said parts formed by said blanks to hold the same in interlocked working position.

12. A toy aeroplane comprising a plurality of blanks cut from sheet material forming a fuselage, a plane, a rudder, a propeller and simulated landing wheels, said blanks having a plurality of tabs formed thereon and a plurality of slots cut therein, certain of said tabs and slots co-operating to assist in holding said parts together, a bail securing a central portion of said fuselage and said plane together, and a propeller shaft securing the forward end of said fuselage together.

In testimony whereof I affix my signature.

HENRY V. DEMPSTER.
